CLAIM

I claim the ornamental design for the charging dock, as shown and described.

DESCRIPTION

FIG. 1 is a front view of a charging dock;
FIG. 2 is a rear view of the charging dock;
FIG. 3 is a top view of the charging dock;
FIG. 4 is a bottom view of the charging dock;
FIG. 5 is a left side view of the charging dock;
FIG. 6 is a right side view of the charging dock; and,
FIG. 7 is a front perspective view of the charging dock.
The broken lines in the figures represent portions of the article which form no part of the claim.
